(57) **CLAIM**

The ornamental design for a drill bit as shown and described.

DESCRIPTION

FIG. 1 is a top, front, left side perspective view of a drill bit showing my new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is an enlarged, sectioned portion highlighted in FIG. 1;

FIG. 9 is an enlarged, sectioned portion highlighted in FIG. 2;

FIG. 10 is an enlarged, sectioned portion highlighted in FIG. 3;

FIG. 11 is an enlarged, sectioned portion highlighted in FIG. 4; and,

FIG. 12 an enlarged, sectioned portion highlighted in FIG. 5. The broken lines having same length dashes in the drawings depict portions of the drill bit that form no part of the claimed design.

The broken lines having long, short dashes represent the boundaries of the enlarged sectioned portions of the claimed design, and form no part thereof.

1 Claim, 9 Drawing Sheets
